CLAIM

The ornamental design for a table lamp, as shown and described.

DESCRIPTION

1.1 is a front elevation view of a table lamp, showing the design;

1.2 is an enlarged top perspective view of the table lamp of **1.1**, showing the design;

1.3 is an enlarged front-right side perspective view of the table lamp of **1.1**, showing the design;

1.4 is an enlarged front-left side-bottom perspective view of the table lamp of **1.1**, showing the design; and

1.5 is an enlarged rear-right side-top perspective view of a balance and a cord of the table lamp of **1.1**, showing the design.

A length of the cord of the table lamp is only claimed up to the broken line demarcation of view **1.5**. A position of the support loop along a length of the tube is repositionable as shown in views **1.1** and **1.2**.
